(57) **CLAIM**

The ornamental design for a camera for television receiver as shown and described.

DESCRIPTION

FIG. 1 is a top, front perspective view of a camera for television receiver showing our new design;

FIG. 2 is a bottom, rear perspective view thereof;

FIG. 3 is a front elevation view thereof;

FIG. 4 is a rear elevation view thereof;

FIG. 5 is a left side elevation view thereof, a right side elevation view being a mirror image thereof;

FIG. 6 is a top plan view thereof;

FIG. 7 is a bottom plan view thereof;

FIG. 8 is a bottom, front perspective view thereof, showing a cradle in broken lines in a folded position; and,

FIG. 9 is another top, front perspective view thereof, shown in a state of use with a television receiver in broken lines. The broken lines in FIGS. 1-8 depict portions of the camera for television receiver that form no part of the claimed design. The broken lines showing the television receiver in FIG. 9 depict environmental structure that form no part of the claimed design.
